UNITED STATES PATENT OFFICE.

GEORGE AMBORN, OF CHAPINVILLE, CONNECTICUT, ASSIGNOR TO J. H. WILLIAMS & CO., OF BROOKLYN, NEW YORK, A CORPORATION OF NEW YORK.

CHAIN PIPE-WRENCH.

1,146,120.

Specification of Letters Patent. Patented July 13, 1915.

Application filed February 19, 1914. Serial No. 819,658.

To all whom it may concern:

Be it known that I, GEORGE AMBORN, a citizen of the United States of America, residing in Chapinville, in the county of Litchfield and State of Connecticut, have invented certain new and useful Improvements in Chain Pipe-Wrenches, of which the following is a specification.

The present invention aims to provide certain improvements in chain pipe wrenches, especially wrenches of the double-jaw type shown in my prior patents, Nos. 876,927 of January 21, 1908, and 952,860 of March 22, 1910.

The invention aims especially to provide a wrench which is simple in construction, and in which the portion of the handle between the jaws can be wider and the swinging link and central stud or pin stronger than in previous wrenches, and in which the chain secures a more perfect grip upon pipes of the smaller sizes.

The accompanying drawings illustrate embodiments of the invention.

Figure 1 is a longitudinal vertical section between the two jaws, showing the chain in elevation. Fig. 2 is a plan of the same, showing only the portion of the chain which is adjacent the lock. Fig. 3 is a section on the line 3-3 of Fig. 2. Fig. 4 is a side elevation of the handle. Fig. 5 is an inside face elevation of one of the jaws. Figs. 6 to 9 inclusive illustrate a slightly modified form of construction embodying the invention. Fig. 6 is a side elevation of the handle, and Fig. 7 a plan view of the same. Fig. 8 is an inside face elevation of one of the jaws. Fig. 9 is a central transverse section of the assembled wrench.

Referring to the embodiments of the invention illustrated, each of the jaws A is of the usual double-ended type having at each end a set of toothed faces B B'. Each jaw has also a central bore C for the central pin D which carries the swinging link E constituting the fixed end of the chain, and has in its opposite end portions bores F F' to receive a fastening bolt G. When the working faces B are to be used the handle is fastened by means of the central pin D passing through the central bore of each of the jaws and by means of the bolt G passing through the bore F' in the rear end of each of the jaws. The handle H projects forward to a point beyond the central pin, as

shown best in Fig. 1, its forward portion being divided into two prongs J J', Fig. 2, between which the swinging link is accommodated. The portions of the prongs J J' which extend forward beyond the pin D are cut away to form recesses K. The chain L is swung around the pipe M in the manner indicated and the upper end of the chain is locked as hereinafter described. The locked end of the chain lies between the upper edges of the jaws, and where a cable chain is used a link lying in an approximately vertical plane comes just over the ends of the prongs J and J' of the handle. Such a link is indicated at N in Fig. 1. This link swings down into the space between the prongs J J' and below the plane of the next link O which is supported on the top of the handle, so that the link N can extend in a substantially straight line toward the pipe, and thus cause the chain to engage the maximum portion of the circumference of the pipes even where they are of comparatively small diameter.

In some constructions the end bolts G are omitted, and the only fastening between the jaws is through a central bolt D. Whether a single bolt or two bolts have been used for this purpose, it has been customary to provide horizontal ledges on the inner faces of the jaws (either integral with the jaws as in my patents above mentioned or fastened on the jaws as in patent to Dickson No. 1,055,148 of March 4, 1913) engaging the top and bottom faces of the handle, so as to prevent angular movement of the jaws relatively to the handle. As the total width between the top and bottom edges of the jaws is limited, so the width of the handle from its top to its bottom face has been further limited by the necessity of fitting it between such ribs. Consequently the central pin and the swinging link have been restricted in size, and with the portion of the handle surrounding the central pin have been found unduly weak compared with the other parts of the wrench. In an application pending concurrently herewith I have described a construction which avoids this difficulty by removing the ledges from the inner faces of the jaws and using as a substitute the horizontal faces of locks which are formed integrally with the jaws and project inward from the inner faces thereof. In the present application I propose to

secure the desired extra width of the handle from top to bottom by making the locks upon the top and bottom faces of the handle and integral therewith, and by extending such top and bottom faces of the handle beyond the inter-engaging projections which are provided for preventing the angular movement of the jaws referred to. For example, the top and bottom faces of the handle may be provided with pairs of locks P backwardly curved and shaped to engage the forward portion of a flat link Q of a cable chain, the next link R lying between the lugs P and between the prongs J and J' while the third link O rests on the top face of the handle between the jaws.

The side faces of the handle and the inner faces of the jaws are provided with inter-engaging projections and recesses lying within the space between the planes of the top and bottom faces of the handle, and the full width of the top and bottom faces of the handle is arranged to directly support the link O and adjacent parts of the chain. The inter-engaging projections and recesses referred to may be of various styles. In Figs. 1 to 5 I have shown the jaws A provided with longitudinal recesses R' into which fit similar projecting ribs S on the side faces of the handle. In Figs. 6 to 9 I have shown the faces of the jaws formed with a central recess T adapted to be engaged by a boss U on the handle, and end recesses V V', one or the other of which will be engaged by a boss W on the handle. By making the projections on the handle the strength of this member is increased as compared with a handle having recessed sides or even plain flat sides. Although I have described with great particularity of detail certain specific embodiments of my invention, yet it is not to be understood therefrom that the invention is restricted to the particular embodiments disclosed.

Various modifications thereof in detail and in the arrangement of the parts may be made by those skilled in the art without departure from the invention.

What I claim is:—

1. A reversible jaw chain pipe wrench having a handle, a pair of double-ended reversible jaws, and a central pin carrying a swinging link forming the fast end of the chain, the side faces of the handle and the inner faces of the jaws being formed with inter-engaging projections and recesses to prevent angular movement of the jaws relatively to the handle, top and bottom faces of

the handle lying beyond the top and bottom of said projections and the entire width of the top and bottom faces of the handle being arranged to directly support the portion of the locked end of the chain which lies between the jaws, whereby the portion of the handle between the jaws is made of maximum width from top to bottom. 60

2. A reversible jaw chain pipe wrench having a handle, a pair of double-ended reversible jaws, and a central pin carrying a swinging link forming the fast end of the chain, the top and bottom faces of the handle being provided with locks, the side faces of the handle and the inner faces of the jaws being formed with inter-engaging projections 70 and recesses to prevent angular movement of the jaws relatively to the handle, said inter-engaging projections and recesses lying within the space between the planes of the top and bottom faces of the handle, and the entire width of the top and bottom faces of the handle being arranged to directly support the portion of the locked end of the chain which lies between the jaws, whereby the portion of the handle between the jaws is made of maximum width from top to bottom. 80

3. A reversible jaw chain pipe wrench having a handle, a pair of double-ended reversible jaws, and a central pin carrying a swinging link forming the fast end of the chain, the side faces of the handle and the inner faces of the jaws being formed with inter-engaging projections and recesses to prevent angular movement of the jaws relatively to the handle, the top and bottom faces of the handle lying beyond the top and bottom faces of said projections. 90

4. A reversible jaw chain pipe wrench having a handle, a pair of double-ended reversible jaws, and a central pin carrying a swinging link forming the fast end of the chain, the side faces of the handle being provided with projections, and the inner faces of the jaws being provided with recesses adapted 100 to be engaged by said projections to prevent angular movement of the jaws relatively to the handle, the top and bottom faces of the handle lying beyond the top and bottom of said projections. 105

In witness whereof, I have hereunto signed my name in the presence of two subscribing witnesses.

GEORGE AMBORN.
